UNITED STATES PATENT OFFICE.

EDWIN SHEPPARD, OF PHILADELPHIA, PENNSYLVANIA.

AUXILIARY HEATER.

SPECIFICATION forming part of Letters Patent No. 518,864, dated April 24, 1894.

Application filed March 6, 1893. Serial No. 464,926. (No model.)

To all whom it may concern:

Be it known that I, EDWIN SHEPPARD, a citizen of the United States, and a resident of Philadelphia, Pennsylvania, have invented 5 certain Improvements in Auxiliary Heaters, of which the following is a specification.

My invention relates to certain improvements in auxiliary heaters for application to the pipes of stoves or furnaces either in the 10 room in which the stove is placed or in a room adjacent thereto.

The object of my invention is to simplify 15 the construction of heaters of this class and to so make them, that the parts can be readily detached so that the interior of the heater can be cleaned without interfering with the piping. This object I attain in the following manner, reference being had to the accompanying drawings, in which—

20 Figure 1, is a longitudinal sectional view of my improved heater. Fig. 2, is a perspective view. Figs. 3 and 4, are detached perspective views. Fig. 5, is a view showing a series of heaters united. Fig. 6, is a sectional view 25 illustrating the application of my improved heater to a vertical pipe. Fig. 7, is a face view showing the heater inclosed within a casing adapted to be set in the wall.

A is the casing made preferably of sheet 30 metal and in the present instance, as shown in the drawings, is quadrangular, but it will be understood that it may be in any form desired without departing from my invention.

35 a is an inlet opening and a' is an outlet opening and adapted to the flanges b b' are the pipes B B' extending from the stove or furnace to the chimney, the openings a a' can be of different diameters according to the size of the pipes B B'.

40 D is a cap snugly fitting the casing A so as to prevent gas from entering the room and depending from this cap are a series of tubes d passing through the cap and secured thereto in any suitable manner and secured to a base 45 plate D' which snugly fits the interior of the lower portion of the casing preventing gas from escaping between the base plate and the casing. The hot air from the stove passes into the casing through the pipe B and circulates around the tubes d, thus heating them 50 and then passes out through the pipe B' to the chimney; the heating of the pipes d causes

the circulation of air through the pipes as indicated by the arrows Fig. 1, consequently the air in the room in which the auxiliary 55 heater is situated is heated to a certain degree.

By making the auxiliary heater as clearly shown in Figs. 3 and 4, that is having the tubes secured to the top and bottom plates 60 and the whole detachable from the casing, the interior of the casing can be cleaned as well as the tubes as all that is necessary is to lift the cover D and remove the parts as shown clearly in Fig. 4, when these parts are 65 cleaned all that is necessary is to insert them in the casing.

I preferably make the auxiliary heaters in small sections and if necessary use a series of these sections as shown clearly in Fig. 5, the 70 sections may simply be coupled together and suspended by the piping or suspended from the ceiling by wires, but I prefer, when using a series, to mount them upon a table or platform E supported by a stand F mounted on 75 the floor, this stand can be adjusted so as to accommodate stoves or pipes of different height. I prefer to form feet on the casing so as to allow the air free access to the interior of the heater. 80

The above described apparatus refers particularly to horizontal piping but where vertical piping is used I prefer the device shown in Fig. 6, which is simply the casing arranged on an incline so that the heat will pass up directly through the casing and the air from the room will traverse the tubes at an incline. The cover plate, tubes and bottom plate are arranged in the same manner, as shown in Fig. 1, so that it may be readily removed and 85 cleansed. 90

In Fig. 7, I have shown the device shown in Fig. 6 duplicated and inclosed within a box having an open front, this is especially applicable for insertion in walls of buildings where 95 the flues are in the walls, the front of the box may be provided with ornamental grill work or a register.

The device shown in Figs. 1 and 6 may be provided with means whereby a water vessel 100 may be adapted to the heater so as to moisten the air.

I claim as my invention—

1. The combination in an auxiliary heater,

of the casing, inlet and outlet for the gas or hot air, with a cover plate, air pipes and bottom plate secured together and removable from the casing, substantially as described.

5. 2. The combination in an auxiliary heater, of the casing, inlet and outlet therefor, a cover plate and tubes secured together and removable from the casing, with a support for the casing independent of the connecting pipes, substantially as set forth.

3. The combination in an auxiliary heater, of the inclined casing, vertical hot air or gas passages with pipes, cover plates and bottom plate, secured together and adapted to the inclined casing, substantially as set forth.

15. 4. The combination in an auxiliary heater, of the series of casings connected together,

inlets and outlets therefor, removable tubes and cover plates adapted to each casing, with a support upon which the several casings rest, substantially as set forth.

5. The combination in an auxiliary heater, of the casing, inlet and outlet for the gas or hot air, with a cover plate overlapping the casing and sealed, a flanged bottom plate 25 adapted to snugly fit in the casing, tubes extending through and attached to both the top and bottom plates whereby the tubes and plates can be removed bodily from the casing, substantially as set forth.

EDWIN SHEPPARD.
